UNITED STATES PATENT OFFICE

JOHN GRANT, OF LOS ANGELES, CALIFORNIA

COMPOUND EXPANDING UNDERREAMER

Application filed December 21, 1927. Serial No. 241,653.

This invention relates to expansive reamers of the type used for drilling or reaming wells, and particularly for reaming or enlarging wells below a casing. Although the 5 form of reamer hereinafter described is designed for rotary drilling, and although the invention is particularly applicable to rotary drilling, it is not necessarily limited or restricted to rotary drilling, as will be 10 seen from the general consideration of the nature of the invention.

The general object of this invention is to provide a reamer which has a comparatively large expansion. Structural limitations 15 and factors of design put a limitation upon the amount of expansion that may be obtained in a given reamer structure; and, particularly in reamers used for rotary work, this limitation has been such as to make it 20 difficult to obtain the amount of expansion necessary to underream large enough to pass a pipe with a tool that will pass through the pipe when contracted. The present practical aspect of my invention is 25 directed to the production of a rotary underreamer that can be passed through a pipe and that will have sufficient expansion below the pipe to ream a hole sufficiently large to allow the pipe to pass freely through it—in 30 other words, a hole substantially larger than the outside of the pipe and its collar.

I accomplish my object by providing a reamer which has two distinct operations of expansion, so cooperating as to give to the 35 cutters an expansion which is the accumulation or addition of two elements of expansion. Thus, in the present typical and illustrative design I provide one element of expansion which is operative by a movement 40 of the cutter with relation to the mandrel on which it is mounted; and another movement of expansion is provided by a movement of the mandrel itself, carrying the cutter with it. This general principle of operation, including independent movement of 45 the cutter with relation to its supporting mandrel, and also movement of the mandrel and cutter together, is applicable to many different forms and designs of expanding 50 reamers. But for the purpose of illustra-

tive description of the invention, I have chosen here to describe the application of the present invention to a form of reamer generally similar to that shown in my application Serial No. 225,270, filed October 10, 55 1927, entitled Expanding roller underreamer. In that type of underreamer, the cutter carrying mandrels, of which, in practice, there are more than one, are eccentrically spaced from the center of the tool 60 body, and roller cutters surround the mandrels and are movable longitudinally thereon, the mandrels and cutters being so formed that longitudinal movement causes projection or expansion of the cutters. Specifically speaking, the application of my present invention to that particular type of expansive reamer consists primarily in giving the mandrels themselves a lateral movement, and preferably a lateral movement of rotation about longitudinal axes. The invention itself, as well as the selected specific adaptation of it, will now be best understood 65 from the following detailed description, reference being had to the accompanying drawings, in which—

Fig. 1 is an elevation of said reamer;

Fig. 2 is an enlarged central longitudinal section of portions of the reamer, both Figs. 1 and 2 showing the tool in contracted position. Figs. 3, 4, 5 and 6 are cross sections taken on lines 3—3, 4—4, 5—5 and 6—6 of Figs. 1 and 2.

Fig. 7 is a view similar to Fig. 2, showing the reamer expanded;

Figs. 8, 9 and 10 are sections on lines 8—8, 9—9, 10—10, respectively, of Fig. 7;

Fig. 11 is a bottom end view of the reamer body;

Fig. 12 is a plan view of the bearing ring, 90 hereinafter described, and located between the reamer body and the sub which extends below the reamer body;

Fig. 13 is a section on line 13—13 of Fig. 7;

Figs. 14 and 15 are diagrammatic views illustrating the expanding and collapsing movements of a mandrel and cutter;

Fig. 16 is a side elevation of a modified form;

Fig. 17 is a central longitudinal section of the modified form; and

Fig. 18 is a plan of the bearing ring which is located at the lower end of the reamer body in the form of Figs. 16 and 17.

In the drawing a suitable body is shown at 10 provided with the usual threaded pin 11 at its upper end for connection with a rotary drill stem. In the particular design 10 here shown I illustrate a reamer having three cutters; the body is accordingly provided with three longitudinally extending slots 12, the particular configuration of which will be hereinafter explained. At the 15 lower end of the body a sub 13 is screwed onto the body, and a bearing ring held in place as illustrated between the body and the sub. This bearing ring, which is non-rotatable with reference to the body and is 20 put in place without the necessity of rotating with reference to the body, forms the bearing element for the lower ends of the cutter supporting mandrels 15, the upper ends of these mandrels being journalled in 25 bores 16 in the upper part of the body above the upper ends of slots 12. Reaching up from the lower end of the body is a cylindric bore 17, the upper end of this bore being above the lower ends of slots 12, so that the 30 lower ends of the slots open into the bore. Propeller actuating sleeve 18 is slidable and rotatable in bore 17 and carries the cutter propeller 19 at its upper end and has a head 20 at its lower end. This head 20, in the 35 uppermost position of sleeve 18, may bear up against the lower end of the screw-threaded pin 10a of the body, the head and sleeve being adapted to move vertically between the positions shown in Figs. 2 and 7, 40 and being pushed up by the action of a spring 21, the lower end of which rests upon a collar 22, the collar in turn resting upon the screw-threaded pin 23 of drilling bit 24 which is attached to the lower end of sub 13. 45 Spring seat collar 22, as shown most clearly in Fig. 13, is provided with peripheral notches or grooves 25, and the bore of sub 13 has lugs or other suitable projections 26, which enter these grooves to prevent relative 50 rotation of spring seat collar 22. Spring 21 acts both as a compression and torsion spring; and when the tool is assembled and the spring seat collar 22 is put in place, it is turned to put the spring under torsional 55 strain, so that the spring is at all times acting to turn sleeve 18 and propeller 19 in a left-handed direction, looking down upon the parts. In order that the spring may have this torsional action, its ends are 60 respectively connected to head 20 and collar 22, as by having its ends, as indicated at 27, set in openings in the head 20 and collar 22, re-

Mandrels 15 have at their ends the upper 65 eccentric bearing pins 35 and the lower

eccentric bearing pins 36, the lower pins being journalled in bores 37 in bearing collar 14. The eccentric axes of bearing pins 35 and 36 are coincidental; and in the diagrammatic Figures 14 and 15 the centers of these bearing pins are designated C. Immediately adjacent the bearing pins each mandrel has a head 38 in the form of a crank; and to facilitate assembly the lower crank head 38 is made removable from mandrel 15. 70 Each mandrel 15 is provided with two fully cylindric parts 40 and with two reduced parts 41, one of the reduced parts 41 being located between the fully cylindric parts 40 and the other reduced part 41 being located below the lower cylindric part 40; so that the mandrel is made up of two spaced fully cylindric parts 40 and two spaced reduced parts 41. The cutter, which is here illustrated as a rotating roller cutter 42, has at 75 or near its ends two cylindric bores 43 of proper size and of proper longitudinal spacing to have a rotating bearing upon mandrel parts 40 when the cutter is in the position shown in Fig. 7. Intermediate the two bearing bores 43 the cutter has an internal bore enlargement as shown at 44, which enlargement fits over the lower mandrel part 40 when the cutters are in the collapsed position shown in Fig. 2, allowing the parts of 80 the cutter at the smaller bores 43 to move back against the mandrel reduced portions 41. This particular interformation of mandrel and cutter causes or allows contractive and expansive movements of the cutter due 85 to relative movement between the cutter and mandrel, specifically due to relative longitudinal movement between the cutter and mandrel; and such interformation, as so far described, is generally similar to that set 90 forth in my co-pending application Serial Number 225,270, filed October 10, 1927, also in my co-pending application Serial Number 122,340, filed July 14, 1926, entitled Expanding roller underreamer; and will need 95 no further particular explanation here except for its particular adaptation to the specific form of double expanding arrangement here described.

By reference particularly to Figs. 14 and 15 it will be seen that the center C^1 of the full mandrel parts 40 is eccentrically offset from center C about which the mandrel rotates. It will also be seen that center C^2 (the center of roller 42 when collapsed) as 100 most plainly shown in Fig. 14, is offset from center C^1 in an inward direction toward the center of the whole tool, when the parts are in their collapsed position as shown in Figs. 2 and 14. The reduced portions 41 of the 105 mandrel are conveniently made by cutting into the outer surface of the mandrel (the surface which is outermost in the collapsed position of Fig. 14), and this cutting is done 110 on center C^2 ; so that the outer surfaces of 115

portions 41, designated 41a in Fig. 14, are of the same curvature radius as the full portions 40 of the mandrel, but are merely offset inwardly. Thus when the cutter is in 5 the collapsed position shown in Figs. 2 and 14 its bores 43 engage the then outer face of reduced portions 41 and have a good flat bearing on those portions, obviating any liability of the bearing surfaces of the roller 10 being scored or mutilated.

The action of expansion in this device involves two different movements of the roller cutter. These movements take place more or less simultaneously, but for clarity of description they may be described successively. Thus one movement of expansion involves the movement of roller 42 upwardly from the position shown in Fig. 2 to the relative position shown in Fig. 7. With the mandrel 15 in the position shown in Fig. 14 and the roller in the lower position shown in Fig. 2, the roller lies inwardly toward the center of the tool; because in that position of the mandrel, the reduced mandrel portions 41 are, as explained before, offset inwardly 20 toward the center of the whole tool. Consequently an upward movement of the cutter to the position of Fig. 7 forces the cutter outwardly by the linear distance represented 25 by the offset of reduced portions 41—the linear distance between centers C¹ and C². To facilitate outward movement of the cutter upon upward movement the lower ends 30 of the full mandrel portions 40 are beveled 35 as indicated at 40a.

With the cutter in full bearing upon the full cylindric mandrel portions 40, then a swinging of the mandrel from the position of Fig. 14 to the position of Fig. 40 15 causes further expansion of the cutter to the fully expanded position, due to the relative eccentric displacement of centers C and C¹. Thus the full and final expansion of the cutter is due to the two 45 movements, one a movement of the cutter relative to the mandrel, the other a movement of the mandrel relative to the body; and the cutter reaches its final and fully expanded position as shown in Figs. 50 7, 8, 9, 10 and 15. In this fully expanded position of the cutter the center C¹ is located substantially radially outwardly from the center C; that is, a radial plane through the center of the whole tool will pass through 55 both center C and center C¹. In this position of the centers rotation of the tool in a right handed direction, looking down upon it, and the reaction pressures against the cutters in a left hand direction, will tend to 60 swing the mandrels further around in a left-handed direction on their centers C. But that, it will be noted, is the same direction in which the mandrels have been swung 65 on their centers for expansive movement of the cutters; and means are provided, here-

inafter explained in detail, not only to stop further swinging of the mandrels in that direction but also to give the cutters direct thrust bearings upon the tool body so as to take torsional and in-thrust strains off the 70 mandrels and their bearings. These matters, however; I will explain in detail after explaining the means by which the cutters are moved relatively to the mandrels and the mandrels are rotated. 75

Propeller 19, which I have before referred to, is mounted upon the upper end of propeller tube 18, and is mounted in such manner as to be rotatively fast upon the propeller tube. For instance, as most clearly 80 shown in Fig. 6, the tube and propeller may interengage with splines 19a. The tendency of spring 21 is at all times to move the propeller upwardly and to swing it around in a left-handed direction, looking down upon 85 it. The propeller has slotted arms 19b which engage the lower parts of mandrels 15 directly under the lower ends of cutters 42. In the lowermost position of the propeller, with the cutters contracted, the propeller lies in the position best shown in 90 Fig. 6, and in this position the mandrels are swung to the collapsed position diagrammatically shown in Figs. 14 and 6. Also in this position it will be noted, by particular 95 reference to Figs. 1 and 6, that the arms of the propellers are prevented from rotating left-handedly by reason of the propeller arms resting against a wall surface 12a of the body slot 12. In this position of the 100 propeller the cutters are consequently in their lower positions as shown in Fig. 2 and the mandrels are in their innermost positions of rotation, as shown in Figs. 6 and 14. As the propeller moves up it moves the cutters upwardly on the mandrels, the cutters resting at their lower ends directly on the 105 propeller. As soon as the propeller arms have moved upwardly to a point above the slotted wall surface 12a, they can then begin to rotate toward the left, as they move upwardly, because of the inclined slotted wall surface shown in Fig. 1 at 12b. Riding this inclined surface 12b the propeller arms move on upwardly and at the same time 110 swing in a left-handed direction until the propeller finally reaches the relative rotative position shown in Fig. 10, and the mandrels reach their relative rotative position, 115 also shown in that figure and in Fig. 15. And when the propeller and the mandrels have thus rotated toward the left to their full extent, the propeller arms then occupy 120 a position bearing against the slotted wall surface shown in Fig. 1 at 12c, and also shown in dotted lines at 12c in Fig. 10, the propeller then being located just under the bearing rib 12d against which the lower cylindric bearing end 42a of the cutter has 125 a thrust bearing when in its expanded posi- 130

tion. The curved bearing face $12e$ of this bearing rib $12d$ is most clearly shown in Fig. 10.

Above the bearing rib $12d$ the slot 12 is shaped merely to provide space for the roller cutter 42 ; but near the upper end of the slot another bearing face $12f$ is provided and against which the upper cylindric bearing end $42b$ of roller 42 has a thrust bearing when in the position shown in Fig. 7. The position of this bearing face $12f$ is shown in Fig. 9 and is indicated in dotted lines in Fig. 7 and is also shown in Fig. 1. Above the bearing face $12f$ the slot has a wall surface $12g$, shown in Figs. 1, 2, 3 and 8 against which the upper head 38 brings up when the parts are in their expanded positions. Likewise in the lower part of the slot there is a similar slotted wall surface $12h$ against which the lower head 38 brings up.

These various bearing surfaces, in the first place, limit the amount of left-handed rotation of the mandrels and in the second place take the thrust strain off the mandrels when the rollers are expanded and are in operation. The direct thrust bearings of the rollers on the body at $12f$ and $12e$ take the combined torsional and inward thrust which is imposed upon the cutters in operation and transmit that thrust directly to the body, without placing any large part of the thrust upon the mandrel and its bearings. However, whatever part of the thrust is placed upon the mandrel is, at the upper end of the mandrel, taken directly by the upper head 38 which has a direct thrust bearing on the body on surface $12g$. And it will be noticed by reference to Figs. 3 and 8 that this surface $12g$ not only prevents further left-handed rotation of head 38 and thus takes directly all torsional strains imposed upon the head, but also it will be noticed that the surface $12g$ curves in behind the cylindric inner end portion of the head so as to take also inward thrust. And at the lower end of the cutter, any strain which is imposed upon the mandrel, from the cutter, tending to rotate the mandrel on around toward the left, is directly transmitted through the propeller arm $19b$ to the body surface $12c$ against which the propeller arm rests in the position of Fig. 7. Consequently, in the construction here explained, substantially all heavy strains which would tend to bend the mandrel are taken off the mandrel and are transmitted directly from the cutter to the body.

Contraction of the cutters, their movement from the position of Fig. 7 to the position of Fig. 2, may be effected merely by pulling the tool up so that the cutters engage the lower end of the casing. Forcing the cutters down relative to the body causes propeller 19 to move down, and the diagonal surface $12b$ causes the propeller to swing

around to its position of Figs. 2 and 6. This enforced swinging of the propeller positively causes swinging of the mandrels from their expanded to their collapsed position, even though in their expanded positions they extend radially outwardly from the center of the tool and therefore could not be swung inwardly merely by straight inward pressure such as would be obtained from contact with the lower end of the casing.

In the form which has now been explained it will be observed that a single spring causes all of the expanding operations of the cutters. But in the form of Figs. 16 to 18 separate springs are provided for the several cutters, as will now be described. In general the body formation in these figures is the same as has been before described, the body slots 12 having the same configurations and the same bearing surfaces as before set forth. Here, however, the slot 12 at its lower end below the diagonal surface $12b$ has a somewhat elongated extension $12j$ for the accommodation of the cutter lifting spring 121 which surrounds the lower extended part $15a$ of the mandrel 15 . The lower end of the mandrel, as before, has the head 38 and the bearing pin 36 of this lower end of the mandrel rotates in a bearing bore $37a$ in bearing collar $14a$, as before described. But in this modification the bore $37a$ is tapered so as to make place for a torsion spring 122 , one end of which is set in a hole 123 in bearing collar $14a$ at the lower end of bore $37a$, and the other end of which is set, as indicated at 124 in Fig. 17, in the end of bearing pin 36 . The spring 122 , of which there is one for each mandrel, tends to rotate the mandrel in a left-handed direction, while the individual springs 121 , one for each mandrel and cutter, tends at all times to elevate the cutter. The general action of this modified form is the same as that hereinbefore described.

It remains only to describe the formation and interlocking arrangement of bearing block 14 and body 10 , which is the same for both forms of the device, the only difference between bearing collar 14 and bearing collar $14a$ being that the latter is thicker in order to accommodate the deeper bores $37a$. This bearing collar is held between the lower end of the body and the sub 13 and has such interengagement with the body as to lock it against relative rotation. The bearing collar has upwardly projecting lugs $14b$ which extend up into the lower ends of the body slots, and it is in these upwardly projecting lugs that the bearing bores 37 or $37a$ are located. Also to strengthen the lower part of the body, the bearing collar is provided with a peripheral upwardly projecting flange $14c$ within which the lower end of the body fits, as best shown at $10c$ in

Figs. 2 and 7. This surrounding of the lower end of the body by the bearing collar flange strengthens the lower slotted end of the body very materially.

- 5 In the form of Figs. 1, etc. a water course to the drill bit 24 is provided by a central bore 100 which is continued on down by a tube 101 that passes through propeller tube 18 and on down through the spring supporting collar 22 and rests either on it or on pin 23 of the drill bit. The entry of the tube into collar 22 serves to steady its lower end and prevent its breakage.
- 10 15

I claim:

- 15 1. In an expansive reamer, a body, a cutter carrying member movable for expansion and contraction with relation to the body, and a cutter mounted exclusively on said carrier and movable with relation thereto 20 for expansion and contraction.

- 20 2. In an expansive reamer, a body, a cutter carrying member swingingly movable about an eccentric axis on the body, and a cutter mounted on the carrier and movable 25 with relation thereto laterally of said axis.

- 25 3. In an expansive reamer, a body, a cutter carrier movable transversely of the body by swinging upon a longitudinal axis, and a cutter mounted on the carrier and movable 30 transversely relatively thereto.

- 30 35 4. In an expansive reamer, a body having a longitudinal axis, a cutter carrying member mounted on and movable with relation to the body in a direction transverse of the body axis, and a cutter mounted on said carrier and movable with relation thereto in a direction transverse of the body axis.

- 40 45 5. In an expansive reamer, a body having a longitudinal axis, a cutter carrier mounted on the body and movable with relation thereto in a direction transverse of the body axis, a cutter carried by the cutter carrier and movable longitudinally thereon, and the carrier and cutter having interengaging formations causing transverse movement of the cutter relative to the carrier by virtue of longitudinal relative movement.

- 50 55 6. In an expansive reamer, a body, a longitudinal cutter carrying mandrel mounted on the body to swing eccentrically about a longitudinal axis, and a cutter mounted on and surrounding the mandrel and movable transversely with relation thereto.

- 60 65 7. In an expansive reamer, a body, a cutter carrying mandrel mounted on the body to swing eccentrically about a longitudinal axis, and a cutter mounted upon and surrounding said mandrel and movable longitudinally with relation thereto, and the cutter and mandrel having interengaging formations causing lateral movement of the cutter relative to the mandrel by virtue of longitudinal movement of the cutter on the mandrel.

- 65 8. In an expansive reamer, a body, a cut-

ter carrier on the body, a cutter carried by said carrier and movable with relation to the body between protracted and retracted positions, and the body having bearing surfaces against which the cutter bears when in protracted position to transmit applied thrust directly from the cutter to the body.

70 9. In an expansive reamer, a body, a cutter carrier mounted on the body, a rotating cutter mounted on the carrier and movable with relation to the body between protracted and retracted positions, and a body and cutter having rotary bearing faces which are engaged when the cutter is in protracted position to transmit applied thrust directly 80 from the cutter to the body.

75 10. In an expansive reamer, a body, a cutter carrier mounted on the body for expanding and contracting movement with relation thereto, a cutter mounted on said carrier for expanding and contracting movement with relation to the carrier, and bearing faces on the body with which the carrier and the cutter engage when in expanded position.

80 90 11. In an expansive reamer, a body having a longitudinal axis, a cutter carrying mandrel mounted on the body for swinging movement about a longitudinal axis between expanded and contracted positions, a rotating roller cutter mounted on and surrounding the mandrel and movable transversely with relation thereto for expansion and contraction, bearing faces on the body adapted to be engaged by the mandrel when 95 in expanded position, and rotary bearing faces on the body adapted to be engaged directly by the cutter when in expanded position.

100 105 12. In an expansive reamer, a body with longitudinal slots therein, arranged symmetrically about the central longitudinal axis of the body, a cutter carrying mandrel in each body slot, said mandrels being arranged to rotate eccentrically about the longitudinal axes which are eccentric of the body axis, whereby said mandrels may be swung to and from positions within the body slots and positions projected from the body slots, cutters mounted upon said mandrels for longitudinal movement with relation thereto, the cutters and mandrels having interengaging formations for causing transverse relative movement of the cutters by virtue of longitudinal relative movement thereof and spring actuated means for swinging the mandrels and for moving the cutters longitudinally.

110 115 13. In an expansive reamer, a body with longitudinal slots therein, arranged symmetrically about the central longitudinal axis of the body, a cutter carrying mandrel in each body slot, said mandrels being arranged to rotate eccentrically about the longitudinal axes which are eccentric of the body axis,

- whereby said mandrels may be swung to and from positions within the body slots and positions projected from the body slots, cutters mounted upon said mandrels for longitudinal movement with relation thereto, the cutters and mandrels having interengaging formations for causing transverse relative movement of the cutters by virtue of longitudinal relative movement thereof, and spring actuated means for swinging the mandrels and for moving the cutters longitudinally, said spring actuated means comprising a cutter propeller movable along and rotatable about the central body axis and slidably engaging the mandrels, and a single spring for moving the propeller longitudinally and also rotating it about the body axis.
14. In an expansive reamer, a body with longitudinal slots therein, arranged symmetrically about the central longitudinal axis of the body, a cutter carrying mandrel in each body slot, said mandrels being arranged to rotate eccentrically about the longitudinal axes which are eccentric of the body axis, whereby said mandrels may be swung to and from positions within the body slots and positions projected from the body slots, cutters mounted upon said mandrels for longitudinal movement with relation thereto, the cutters and mandrels having interengaging formations for causing transverse relative movement of the cutters by virtue of longitudinal relative movement thereof, and spring actuated means for swinging the mandrels and for moving the cutters longitudinally, said spring actuated means comprising a cutter propeller movable along and rotatable about the central body axis and slidably engaging the mandrels, and a single spring for moving the propeller longitudinally and also rotating it about the body axis, the body slots having diagonally extending walls which cause rotation of the cutter propeller in one direction by virtue of longitudinal movement of the propeller in one direction.
15. In an expansive reamer, a body with longitudinal slots therein, arranged symmetrically about the central longitudinal axis of the body, a cutter carrying mandrel in each body slot, said mandrels being arranged to rotate eccentrically about the longitudinal axes which are eccentric of the body axis, whereby said mandrels may be swung to and from positions within the body slots and positions projected from the body slots, cutters mounted upon said mandrels for longitudinal movement with relation thereto, the cutters and mandrels having interengaging formations for causing transverse relative movement of the cutters by virtue of longitudinal relative movement thereof, and spring actuated means for swinging the mandrels and for moving the cutters longitudinally, said spring actuated means comprising a cutter propeller movable along and rotatable about the central body axis and slidably engaging the mandrels, and a single spring for moving the propeller longitudinally and also rotating it about the body axis, the body slots having bearing faces against which the mandrels bear when in protracted position, and having also bearing faces against which the cutters bear when in protracted position.
16. In an expansive reamer, a body having a longitudinal central axis, a longitudinally extending cutter carrying mandrel mounted on the body to swing with relation thereto about an axis eccentric of the body axis, a cutter carried by the mandrel and movable longitudinally thereof, the cutter and mandrel having interengaging formations adapted to cause lateral movement of the cutter by virtue of its longitudinal movement on the mandrel, and a spring actuated means for causing swing movement of the mandrel and longitudinal movement of the cutter.
17. In an expansive reamer, a body having a longitudinal central axis, a longitudinally extending cutter carrying mandrel mounted on the body to swing with relation thereto about an axis eccentric of the body axis, a cutter carried by the mandrel and movable longitudinally thereof, the cutter and mandrel having interengaging formations adapted to cause lateral movement of the cutter by virtue of its longitudinal movement on the mandrel, and a single spring actuated means for causing both swinging movement of the mandrel and longitudinal movement of the cutter.
18. In an expansive reamer, a body having a longitudinal central axis, a longitudinally extending cutter carrying mandrel mounted on the body to swing with relation thereto about an axis eccentric of the body axis, a cutter carried by the mandrel and movable longitudinally thereof, the cutter and mandrel having interengaging formations adapted to cause lateral movement of the cutter by virtue of its longitudinal movement on the mandrel, and a single spring actuated means for causing both swinging movement of the mandrel and longitudinal movement of the cutter.
19. In an expansive reamer, a body having a longitudinal central axis, a longitudinally extending cutter carrying mandrel

axis, the body slots having bearing faces against which the mandrels bear when in protracted position, and having also bearing faces against which the cutters bear when in protracted position.

16. In an expansive reamer, a body with longitudinal slots therein, arranged symmetrically about the central longitudinal axis of the body, a cutter carrying mandrel in each body slot, said mandrels being arranged to rotate eccentrically about the longitudinal axes which are eccentric of the body axis, whereby said mandrels may be swung to and from positions within the body slots and positions projected from the body slots, cutters mounted upon said mandrels for longitudinal movement with relation thereto, the cutters and mandrels having interengaging formations for causing transverse relative movement of the cutters by virtue of longitudinal relative movement thereof, and spring actuated means for swinging the mandrels and for moving the cutters longitudinally, said spring actuated means comprising a cutter propeller movable along and rotatable about the central body axis and slidably engaging the mandrels, and a single spring for moving the propeller longitudinally and also rotating it about the body axis, the body slots having diagonally extending walls which cause rotation of the cutter propeller in one direction by virtue of longitudinal movement of the propeller in one direction.

17. In an expansive reamer, a body having a longitudinal central axis, a longitudinally extending cutter carrying mandrel mounted on the body to swing with relation thereto about an axis eccentric of the body axis, a cutter carried by the mandrel and movable longitudinally thereof, the cutter and mandrel having interengaging formations adapted to cause lateral movement of the cutter by virtue of its longitudinal movement on the mandrel, and a spring actuated means for causing swing movement of the mandrel and longitudinal movement of the cutter.

18. In an expansive reamer, a body having a longitudinal central axis, a longitudinally extending cutter carrying mandrel mounted on the body to swing with relation thereto about an axis eccentric of the body axis, a cutter carried by the mandrel and movable longitudinally thereof, the cutter and mandrel having interengaging formations adapted to cause lateral movement of the cutter by virtue of its longitudinal movement on the mandrel, and a single spring actuated means for causing both swinging movement of the mandrel and longitudinal movement of the cutter.

19. In an expansive reamer, a body having a longitudinal central axis, a longitudinally extending cutter carrying mandrel

5 mounted on the body to swing with relation thereto about an axis eccentric of the body axis, a cutter carried by the mandrel and movable longitudinally thereof, the cutter and mandrel having interengaging formations adapted to cause lateral movement of the cutter by virtue of its longitudinal movement on the mandrel, a cutter propeller movable along and rotatable about the body axis
10 and slidably engaging the mandrel in contact with a cutter, and a single spring for moving the cutter propeller longitudinally and for rotating it about the body axis.

20. In an expansive reamer, a body, a cutter carrying member movable for expansion and contraction with relation to the body, and a cutter on said carrier and movable with relation thereto for expansion and contraction independently of the expansive and contractive movements of the carrier with relation to the body.

In witness that I claim the foregoing I have hereunto subscribed my name this 13th day of December, 1927.

JOHN GRANT.
